UNITED STATES PATENT OFFICE.

JAMES F. FEEHERY, OF COLLINGDALE, PENNSYLVANIA.

WORK-HOLDING APPLIANCE.

Application filed March 6, 1925. Serial No. 13,632.

My invention relates to work-holding appliances, particularly to work-holding appliances which are especially adapted for use with grinding machines, and it has for 5 an object to provide apparatus of the character designated which shall be of staunch and rugged construction and capable of readily supporting various forms of work having relatively different shapes and contours. It 10 has for a further object to provide a holding appliance which shall admit of the work being quickly removed and replaced and which shall include facilities for accurately aligning the work with respect to the grinding 15 wheel.

These and other objects, which will be made apparent throughout the further description of my invention, may be attained by the employment of the apparatus herein- 20 after described and illustrated in the accompanying drawings, in which Fig. 1 is a view, in elevation, of one form of my novel appliance; Fig. 2 is a transverse view, partly in elevation and partly in section, of the ap- 25 paratus shown in Fig. 1; Fig. 3 is a plan view of one of the dogs or work retaining members employed in my appliance; Fig. 4 is a view, in sectional elevation, taken on the line IV—IV of Fig. 2, and Fig. 5 is a view, 30 in elevation, showing the application of my work-holding appliance to a well known form of grinding machine.

In the process of grinding miscellaneous pieces of work having various shapes and contours, it has generally been the custom to secure the work upon the table of the grinding machine by improvising for each piece of work a support formed by an aggregation of clamps, blocks, bolts, washers, etc. Frequently, the time consumed by the operator 40 of the machine in the fabrication of such a support is considerably in excess of the time consumed in the actual grinding process.

I have therefore evolved a novel form of 45 work-supporting appliance which is adapted to be secured to the table of any grinding machine and which is capable of not only securing pieces of work having relatively different forms but also pieces of work of 50 very irregular form. Briefly speaking, my appliance comprises an angle plate for vertical face grinding provided with two or more dogs, or work retaining members which may be located in any relative position upon 55 the angle plate. However, the retaining members may be mounted on the machine

table or base as to permit of horizontal grinding. One or more of the dogs is provided with a novel form of clamping mechanism whereby the work may be rapidly secured in place. Adequate facilities for correctly aligning the work are provided. By means of such an appliance, the amount of work produced by a single grinding machine acting upon pieces of work of various shapes and contours has been materially increased, the idle periods of the machine or, in other words, the time involved in admitting work to and removing work from the machine, being reduced to a minimum. 70

Referring to the drawings for a more detailed description of my invention, I show in Figs. 1 and 2 a piece of work, such as a sole plate 10 having a surface 11 to be ground. As illustrated, the sole plate 10 is held in one form of my novel supporting appliance which is adapted to be secured to the table of a grinding machine as represented at 12. The appliance comprises an angle plate 13 which has provided in one of its faces a plurality of parallel spaced vertical and horizontal T slots 14 and 15. Secured in the T slots 14, as by bolts 16, are upper and lower work supporting members 17 and 18. The work supporting members 17 are, in turn, 80 provided with a T slot 20 and a feed screw 19 for permitting the adjustment of the work supporting member to any position intermediate of the slots. While I have shown the work supporting members as being carried in the vertical slots 14, it is to be understood that the angle plate is so constructed that the supporting members may be inserted horizontally, the manner of their insertion being determined solely by the contour of the piece of work supported. As illustrated, the lower work supporting members 18 are bolted to the angle plate and supported upon the table 12 of the grinding machine. However, it is apparent that the lower supporting members 85 may be entirely supported from the angle plate. 90

To the lower work retaining member 18 is attached a hardened clamping plate 21 having a portion of its surface serrated, striated, knurled or defaced in a manner such as will prevent the work from slipping or from becoming dislodged. The upper work retaining member 17 is provided with a yoke end 22 within which is fulcrumed a lever 23 by means of a pin 24. The lever 23 is also provided with a yoke end 25 within which a 100 105 110

jaw 26 is fulcrumed at 27. The jaw 26 is also hardened and provided with a serrated surface 28 for preventing the work from becoming dislodged. Provided in the opposite end of the lever 23 is a jack screw 29 which bears against an inclined surface 31 provided upon the supporting member.

Projecting from each of the supporting members 17 and 18 is a lug 32 within which is threaded an adjusting screw 33 for positioning the work. In addition, a ratchet bar 34 is also provided for establishing a datum plane for facilitating the positioning of the work. A pawl 35 is associated with the ratchet bar 34 in such a manner as to prevent freedom of movement toward the angle plate. A spring 36 is provided for holding the pawl in engagement with the ratchet bar and a button 37 is provided on the pawl for manually releasing the same from the ratchet bar.

The method of employing the above form of work holder is as follows:

The upper and lower work supporting members 17 and 18 are positioned upon the angle plate 13 to correspond with the contour of the work to be ground. The manner of securing these supporting members is well known in the machine tool art. The screws 33 are then adjusted so that the surface 11 of the work to be ground is normal to the table 12. Very frequently, the surface opposite that to be ground is rather irregular and requires that each screw be adjusted to a different position. Upon the screws 33 being adjusted to suit the work, the work 10 is fixedly secured in place by manipulating the jack screw 29, the upward movement of this end of the lever forcing the jaw 26 against the work. The jaw 26 being suitably located and journaled in the lever 23, adjusts itself to the surface of the work irrespective of the position of the lever. The work is thus rigidly secured in place and the actual process of grinding may be proceeded with.

It is sometimes required to grind the two opposite faces of a piece of work. In this instance, the adjusting screws 33 may be employed to position the work for grinding the first face, after which these screws are moved out of position and each ratchet bar 34 is drawn away from the face plate an equal number of notches. The four ratchet bars therefore form a datum plane, which is exactly parallel with the face of the angle plate. One surface of the work having been ground, this surface is placed against the four ratchet bars 34, the lever 23 is employed to secure the work in place, and the grinding of the second face may be proceeded with. The two oppositely disposed faces are thus ground exactly parallel.

It is apparent from the foregoing description of my invention, that I have invented

a form of supporting appliance which permits of the work being quickly removed and replaced and which has facilities for very accurately aligning the work with respect to the table of the grinding machine. While I have shown four work supporting members in Fig. 1, I may provide any number as may be required to adequately support the work. Furthermore, while I have described my invention as being especially applicable to grinding machines, nevertheless it is to be understood that it is within the purview of my invention to employ this appliance with any form of tool mechanism for supporting the work therein in any desired relative position to the cutting tool. In employing this appliance in conjunction with various machine tools such as milling machines, boring mills, planers, etc., suitable work stops and supports may be provided.

In Fig. 5, I have shown the application of my novel work supporting appliance to one form of grinding machine 41. The machine 41 is provided with a circular grinding wheel 42 driven by a motor 43 through suitable gearing 44. The work 10 in contact with the grinding wheel is firmly secured in my work holding appliance which is in turn supported upon the table 45 of the machine. It is apparent from this illustration that my appliance may be readily applied to any standard form of grinding machine without requiring any alterations whatsoever to the machine.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art, or as are specifically set forth in the appended claims.

What I claim is:

1. In a work-holding appliance, the combination of a base structure having a working surface, a plurality of independent work-supporting members, each of said work-supporting members having attaching means for rigidly engaging said working surface in any desired position relative to each other, means associated with each work-supporting member and adjustable in a direction toward or away from said working surface for establishing datum points for positioning the work, each of said work-supporting members having embodied therein a work-engaging surface adapted to receive or exert a thrust in a plane substantially parallel to said working surface, and individual means embodied in some of the work-supporting members for effecting such thrust.

2. In a work-holding appliance, the combination of a face plate having a working

- surface, a plurality of independent work-supporting members, attaching means associated with each work-supporting member for rigidly engaging the working surface 5 of the face plate in any desired position relative to each other, means carried by each work-supporting member and adjustable in a direction toward or away from the working surface of the face plate for establishing datum points for positioning the work, each of said work-supporting members being provided with a work-engaging surface adapted to receive or exert a thrust in a plane substantially parallel to the working 10 surface of the face plate, and individual clamping mechanism associated with some of the work-supporting members for effecting such thrust.
3. In a work-holding appliance, the combination of a face plate having a working surface, a plurality of independent work-supporting members, attaching means associated with each work-supporting member for fixedly engaging the working surface 15 of the face plate in any desired position relative to each other, projections provided on each work-supporting member, means carried in the projections and adjustable in a direction toward or away from the working surface of the face plate for positioning the work, fixed work-engaging surfaces provided in some of the work-supporting members and adapted to receive a thrust in a plane substantially parallel to the working surface of the face plate, a lever fulcrumed upon each of the remaining work-supporting members, and a work-engaging element associated with each lever and movable angularly with respect thereto, each of said work-engaging elements and associated levers being so arranged as to exert a thrust 20 in a direction substantially parallel to the working surface of the face plate.
4. In a work-holding appliance, the combination of a face plate having a working surface, a plurality of independent work-supporting members, attaching means associated with each work-supporting member for fixedly engaging the working surface of the face plate in any desired position relative to each other, projections provided on each work-supporting member, means carried in the projections and adjustable in a direction toward or away from the working surface of the face plate for positioning the work, fixed work-engaging surfaces provided in some of the work-supporting members and adapted to receive a thrust in a plane substantially parallel to the working surface of the face plate, a lever fulcrumed upon each of the remaining work-supporting members, and a work-engaging element associated with each lever and movable angularly with respect thereto, each of said work-engaging elements and associated levers being so arranged as to exert a thrust 25 in a direction substantially parallel to the working surface of the face plate.
5. In a work-holding appliance, the combination of a face plate having a working surface, a plurality of independent work-supporting members, attaching means associated with each work-supporting member for fixedly engaging the working surface 30 of the face plate in any desired position relative to each other, projections provided on each work-supporting member, means carried in the projections and adjustable in a direction toward or away from the working surface of the face plate for positioning the work, fixed work-engaging surfaces provided in some of the work-supporting members and adapted to receive a thrust in a plane substantially parallel to the working surface of the face plate, a lever fulcrumed upon each of the remaining work-supporting members, and a work-engaging element associated with each lever and movable angularly with respect thereto, each of said work-engaging elements and associated levers being so arranged as to exert a thrust 35 in a direction substantially parallel to the working surface of the face plate.

In testimony whereof, I have hereunto subscribed my name this twenty-fifth day of February, 1925.

JAMES F. FEEHERY.
